UNITED STATES PATENT OFFICE.

LAHVESIA P. C. PACKWOOD, OF LAKE MAITLAND, FLORIDA.

DESIGN FOR A BADGE.

SPECIFICATION forming part of Design No. 29,529, dated October 25, 1898.

Application filed September 17, 1898. Serial No. 691,244. Term of patent 3½ years.

To all whom it may concern:

Be it known that I, LAHVESIA P. C. PACKWOOD, a citizen of the United States, residing at Lake Maitland, in the county of Orange and State of Florida, have invented and produced a new and original Design for a Badge, of which the following is a specification, reference being had to the accompanying drawing, forming a part thereof, which represents a plan view of a badge embodying the features of my design.

The design consists of a plate A, upon which appears the representation of a pig, and a pendent plate B, upon which is represented a human male figure. The two plates are connected by a link b, and the male figure is represented in a kneeling position. The plate

upon which the kneeling figure is represented is of diamond or lozenge shape, while the main plate is practically rectangular. 20

The leading feature of the design consists in two plates, one pendent from the other, one plate having the representation of a pig produced thereon and the other plate being decorated with the representation of a man 25 in a kneeling position.

I claim—

The design for a badge, herein shown and described.

LAHVESIA P. C. PACKWOOD.
